UNITED STATES PATENT OFFICE.

DINSHAW JINABHOY AKHOONA, OF BULSAR, BOMBAY PRESIDENCY, INDIA.

PREVENTING COLLISIONS ON RAILWAYS.

1,402,993.

Specification of Letters Patent. Patented Jan. 10, 1922.

Application filed June 23, 1920. Serial No. 391,008.

To all whom it may concern:

Be it known that I, DINSHAW JINABHOY AKHOONA, a subject of the Emperor of India, residing at Bulsar, Bombay Presidency, 5 India, have invented certain new and useful Improvements in Preventing Collisions on Railways, of which the following is a specification.

This invention is intended to prevent collisions on a single line of railway, by enabling each train to operate the vacuum brakes of the other train to ensure stoppage while yet at a safe distance apart.

Hitherto precautions have taken the form 15 of signals, operated by an advancing locomotive or train or otherwise which have not been reliable.

The present invention provides an automatic arrangement which acts on the 20 vacuum brakes and stops a train at a distance from the one approaching from the opposite direction. It consists of a flat iron bar resting on roller guides near the inner side of both rails. Beneath the bar and 25 above each roller are wedge shaped projections so that when the bar is moved horizontally it will rise in level to the extent of about 3 inches. Bars of suitable length are used to allow two approaching trains to 30 come to rest under the influence of their brakes without meeting. The ends of the bars are connected by short horizontal chains 35 passing over grooved pulleys and terminating in a vertical plunger that is actuated from above by a sloping lever whose lower end is fixed near the level of the rail and which may be depressed by a wheel or roller suspended from the front part of the engine as it passes over the lever. This wheel is connected by 40 a rod and lever to the reversing lever of the engine so that it may be thrown out of action when the engine is backing. The automatic controlling gear is fixed on the left hand side of each engine and this acts upon the 45 right hand side of an approaching engine. When the sliding bar is raised by one engine on its left hand side it lifts a slipper suspended from the right hand side of the approaching engine or train which slipper causes a valve or cock to open on the vacuum main and throws on the brakes.

The invention is shown on the annexed drawings in Figures 1 to 5, Figure 1 being a longitudinal elevation, Fig. 2 a plan view, 55 Fig. 3 a cross-sectional view, Fig. 4 a view similar to Fig. 1, but showing the parts in

different positions and Fig. 5 a view of a detail.

Fig. 1 shows the arrangement in longitudinal elevation of the sliding bars *b* and *b'*, 60 the guide rollers *g* and *h* and the chain rollers *f*, *f*. The chains are attached at one end to the sliding bars *b*, *b'* and at the other end to the plunger *d*, whose upper end is jointed to the lever *e*, that is connected by 65 hinges *m*, *m*, to a sleeper, see Fig. 2. In Fig. 1 the sliding bar *b* is level with the rail *a* and the bar *b'* is resting on a wedge shaped projection *q* which raises it about 3 inches above the level of the rails. The lever *e* is 70 also raised.

Referring to Fig. 4 the same parts are in a new position caused by the advance of the wheel *i* upon the lever *e* which forces it down to the level of the rails depressing the 75 plunger and pulling the sliding bars *b*, *b'* into new positions. The bar *b* is now raised about 3 inches above the level of the rails and the bar *b'* is correspondingly depressed. The wheel *i* is hung from a bar *j* suspended 80 between the frames of the engine and connected through *k* and *s* with the reversing lever on the footplate so that when the engine is backing the wheel *i* is lifted clear of all obstruction. A stop *r* bearing against 85 the framing keeps the wheel *i* in working position.

Fig. 5 is a slipper *n* suspended from a bar *o* so as to be immediately above the sliding bars *b*, *b'*, it is attached to the framing of 90 the engine or tender and carries a rod *p* which when the slipper *n* is raised will open a valve or cock on the vacuum main and apply the brakes. Thus with the bar *b* in 95 position as shown in Fig. 4 the slipper of the advancing train (on the left) would be raised on coming in contact with the bar *b* and would apply the brakes of that train. The two trains approaching would act reciprocally and stop each other.

Fig. 2 is a plan of the invention showing 100 the lever *e* the sliding bars *b*, *b'* the rollers *f*, *g*, *h* and the rails *a* in their respective positions.

The direction in which the device acts in 105 the approaching trains is indicated by arrows, Fig. 2.

Fig. 3 is a cross section of the line through 110 centres of rollers *g* and *f* showing the brackets on which they are carried and their bed on the longitudinal sleepers *l*. With the aid of the above invention an engine is

constantly preparing in advance the means of throwing on the brakes of an approaching train while at a safe distance so as to cause the approaching train to come to rest before 5 a collision can take place.

What I claim as my invention and desire to secure by Letters Patent is:

1. The combination with the rails of a railroad-track and sleepers for said rails, of 10 longitudinally movable bars disposed along the inner side of the rails, means connecting the said bars, an intermediate member between the said bars included in said connecting means, and an actuating member for said 15 intermediate member so arranged as to move and simultaneously raise either of said bars

above the level of the rails when engaged by a part of a train passing over said rails for the purpose described.

2. In the combination as specified in claim 20 1, roller guides for said bars, and projections on the latter for raising them above the level of the rails, as the said bars are moved longitudinally.

In testimony whereof I have signed my 25 name to this specification in the presence of two subscribing witnesses.

DINSHAW JINABHOY AKHOONA.
